UNITED STATES PATENT OFFICE.

WILBERT J. SHUART, OF DETROIT, MICHIGAN.

SEPARABLE SQUARE.

No. 911,846.

Specification of Letters Patent.

Patented Feb. 9, 1909.

Application filed December 14, 1907. Serial No. 406,426.

To all whom it may concern:

Be it known that I, WILBERT J. SHUART, a citizen of the United States, residing at Detroit, in the county of Wayne, State of Michigan, have invented certain new and useful Improvements in Separable Squares; and I do declare the following to be a full, clear, and exact description of the invention, such as will enable others skilled in the art to 10 which it appertains to make and use the same, reference being had to the accompanying drawings, and to the figures of reference marked thereon, which form a part of this specification.

15 This invention relates to new and useful improvements in squares, and consists in the construction and arrangement of parts hereinafter fully set forth and claimed.

The object of the invention is to produce a 20 square for artificers wherein the arrangement is such as to enable the right angle parts of the square to be readily separated so that they may be placed side by side for convenience in packing the implement in a tool 25 box or for shipping, provision being made for securing the parts together in a manner to retain them properly in place without interfering with the use of the implement.

The above object is attained by the structure illustrated in the accompanying drawings, in which—

Figure 1 is a plan view of a square involving my invention, parts being broken away. Fig. 2 is a similar view showing the right angle members detached. Fig. 3 is an exaggerated longitudinal section as on line 3—3 of Fig. 1. Fig. 4 is an exaggerated transverse section as on line 4—4 of Fig. 1. Fig. 5 is a fragmentary view in perspective, showing 40 the members of the square detached, the graduations being omitted therefrom. Fig. 6 is an exaggerated transverse section as on line 6—6 of Fig. 1.

Referring to the characters of reference 1 45 designates the wide blade or member of the square, and 2 the relatively narrow blade or member. Projecting at right angles from the member 1 are the opposed arms 3 having between them the longitudinally extending 50 tapered slot 4, said arms lying in the plane of the member 1 and having at their outer ends the tenons 5. Projecting centrally into the slot 4 from the member 1 is a spring catch 6 which lies in the plane of the arms 3 and 55 which for the greater portion of its length is one-half the thickness of the material of the

square, the outer end of said catch being equal in thickness to the thickness of the square in order to form a shoulder 7, and being beveled, as at 8, to facilitate the placing 60 of the separable parts of the square together, as hereinafter explained. The inner edge of each of the arms 3 is provided with a groove, and the opposite edges of the tenons 5 are also grooved for purposes hereinafter 65 explained.

The member 2 of the square is provided at its inner end with a projecting tapered blade 9 adapted to enter the tapered slot between the arms 3, and having marginal tongues 10 70 adapted to enter the grooves in the inner edges of said arms, as clearly shown in Fig. 4. The inner end of the blade 9 is provided with a longitudinal recess 11 equal in depth to half the thickness of said blade adapted to 75 receive the spring catch 6, said blade having at the terminal of said recess an aperture 12 into which the enlarged end of the spring catch is adapted to enter and the margin of which is adapted to be engaged by the 80 shoulder 7 of said catch to lock said parts together. At the base of the blade 9 of the member 2 are the mortises 13 into which the tenons 5 on the outer ends of the arms 3 are adapted to enter, the marginal projections 85 14 of the member 2 having the tongues 15 which enter the outer marginal grooves in the tenons 5 and in the outer ends of the arms 3.

To join the parts or members of the square, 90 the blade 9 of the member 2 is inserted longitudinally into the slot between the arms 3 of the member 1, the marginal tongues of the blade 9 entering the grooves in the edges of said arms and the spring 95 catch 6 engaging and lying in the recess 11 and aperture 12 in said blade, whereby the members of the square become rigidly locked together in the same plane. The tenons 5 on the arms 3 entering the mortises at the 100 base of the tongue of the member 2 prevent the spreading of said arms 3 and assist in securely locking all of the parts in alinement, thereby obviating any projecting part to interfere with the use of the square. By 105 this means of uniting the parts or members of the square, they become rigidly joined at right angles in a manner to enable them to be readily detached or separated, when desired.

To separate the parts of the square, it is only necessary to spring the catch 6 out-

wardly so as to disengage the shoulder 7 at the end thereof from the aperture 12, when said parts may be detached by drawing longitudinally upon the part 2.

5 By this arrangement the right angle members of the square may be readily separated, enabling the square to be easily placed in a tool box without any part thereof projecting from said box, obviating the necessity of 10 cutting a slit in the tool box for the protrusion of the end of the square, as commonly practiced.

Having thus fully set forth my invention, what I claim as new and desire to secure by 15 Letters Patent, is:—

1. A square consisting of separable parts, one part having opposed arms projecting at right angles therefrom in the plane thereof, said arms having marginal grooves, the other 20 part having a projecting blade in alinement therewith adapted to enter between said arms and having marginal tongues which enter the grooves thereof, a spring catch

upon one of said parts projecting centrally between said arms, the blade of the other 25 part being fashioned at its outer end to be engaged by said catch to lock the parts of the square together.

2. A square comprising separable parts, one part having opposed arms projecting at 30 right angles therefrom in the same plane, and inclined on their inner edges to form a tapered opening between them and a spring tongue extending between said arms in the plane thereof, the other part having an 35 extending tapered blade adapted to enter between said arms, means for preventing lateral movement between the arms and blade, the end of said blade having a recess to receive said spring tongue.

In testimony whereof I sign this specification in the presence of two witnesses.

WILBERT J. SHUART.
